UNITED STATES PATENT OFFICE

2,085,314

MATCH SAFE

Bertis F. Hamilton, Columbus, Ind.

Application December 12, 1935, Serial No. 54,013

3 Claims. (Cl. 206—20)

It is the object of my invention to produce a device suitable for containing matches, toothpicks, or similar articles and for holding them in such a manner that they may be easily withdrawn 5 one at a time. More specifically, it is my object to produce a device of this kind which can be simply and economically manufactured and which will be attractive in appearance.

In carrying out my invention I preferably form 10 the base of the device of some relatively heavy material, such as cast iron, in order to increase stability, and on this base I support the container proper, which conveniently is formed of sheet metal. The bottom of the container is formed 15 by two downwardly converging walls one of which is cut away to provide access for a thumb or finger used in grasping the articles which the box contains. The box may have any desired number of compartments for the reception of various articles.

The accompanying drawing illustrates my invention: Fig. 1 is an isometric view of a complete device embodying a compartment for matches to be dispensed, a compartment for toothpicks 25 to be dispensed, and a burnt-match compartment located above the toothpick compartment; Fig. 2 is a vertical section on the line 2—2 of Fig. 4; Fig. 3 is a vertical section on the line 3—3 of Fig. 4; Fig. 4 is a horizontal section on the line 4—4 of 30 Fig. 3; Fig. 5 is an isometric view illustrating the manner in which the parts of the sheet-metal container are formed and assembled; and Fig. 6 is a fragmental section illustrating the means by 35 which the sheet-metal container is supported on the base.

As previously indicated, the container illustrated in the drawing contains two compartments for articles to be dispensed. The vertical walls of the container 10 are conveniently formed of a 40 single piece of sheet metal bent in rectangular form, the container being divided interiorly by a vertically extending sheet-metal partition 11 having along its side edges flanges which may be secured to the front and back walls of the container-body, as by spot-welding. The open upper 45 end of the container is closed by a cover 12, the edges of which are turned downwardly at right angles to engage the outer surfaces of the vertical 50 walls of the container-body 10. Between the center partition 11 and each end wall of the container I cut out and bend inwardly into an inclined position a tongue 13, as indicated in Figs. 2 and 3, thus leaving for each of the compartments 55 of the container an opening in the front wall

through which articles within the container may be withdrawn.

The bottom of each compartment of the container is formed by a piece of sheet-metal 14 bent medially along a longitudinal line into a trough shape. The extreme rear edge of each of the bottoms 14 is bent downwardly into a flange 15 adapted to be secured to the inner face of the back wall of the container-body 10, as by spot-welding. The front edge of the sheet-metal bottom 14 is provided with a notch 16 extending inwardly approximately to the bottom of the trough which the sheet-metal member 14 forms, and the front edges of the sheet-metal members 14, on opposite sides of the notch 16, are bent downwardly to provide flanges 17. In cutting the notch 16 in the blank from which the bottom 14 is formed, I provide triangular flaps 18 on each side of the notch, such flaps in the finished bottom being bent into a vertical plane as indicated in Fig. 5.

The strip of metal lying between the bottom of the front wall and the lower edge of the opening formed by the inward bending of each tongue 13 is cut through at a central point, and the material 25 on each side of the cut is bent inwardly and back upon itself to form a tongue 19 spaced from the front wall of the container-body 10 to provide for the reception of one of the flanges 17 at the front edge of the bottom-piece 14. In Fig. 5, the bottom piece 14 is illustrated in finished form above the position it will occupy. When the bottom-piece 14 is lowered, the flanges 17 will be received 30 between the front wall of the container-body 10 and the inwardly bent tongues 19. The final position of the bottom piece 14 will be determined 35 by engagement of the upper edges of the tongues 19 with the lower surface of the bottom piece along the line on which the flanges 17 are bent; and the lower edges of the flaps 18 will be disposed substantially in the end plane of the container-body.

The base of the container, as previously indicated, is preferably in the form of an iron casting 21. Conveniently, the base is formed beneath 45 each of the notches 16 with a depression 22 to facilitate the entrance of the thumb or finger used in grasping one of the articles supported on the bottom-piece 14. To secure the container-body 10 to the base 21, each of the bottom-pieces 50 14 may be provided with an opening 23 for the passage of a bolt 24 extending through the wall of the base 21, as indicated in Fig. 6.

If desired, one of the compartments into which the container is divided by the partition 11 may 55

be subdivided by a horizontal partition 25 defining the bottom of a burnt-match compartment. If this is done, the cover 11 above the burnt-match compartment is provided with an opening 26 along the side edges of which are disposed baffles 27 and 28 such as set forth in my prior Patent No. 2,008,016. If the device is to be used to dispense matches and toothpicks, the partition 25 is desirably located in the toothpick compartment.

The match compartment may be filled by removing the cover 12, and the matches inserted. If desired, the match compartment may be made large enough to receive the match box, the end 15 of which has been torn out to permit the matches to drop into engagement with the bottom 14 of the compartment. The toothpick compartment may be filled by laying the device on its back and introducing the toothpicks through 20 the opening in the front wall.

When the device is in erect position, the toothpicks and matches will be supported on the inclined ledges formed by these portions of the bottom piece 14 at the sides of the notch 16, 25 and some of them will bridge each notch 16 where they are in a position such that they can be readily grasped. The tongue 13 prevents the toothpicks or matches from spilling outwardly through the opening in the front wall of each 30 compartment.

Conveniently, the front surface of the base 21 is provided with a roughened pad 30 on which matches may be struck.

I claim as my invention:

35. 1. In a device of the type described, a sheet-metal container having a substantially vertical

front wall, a bottom for said container and also formed of sheet-metal, the front wall of said container being provided above its lower edge with a horizontally extending opening the material from which is bent along the upper edge 5 of the opening to provide a downwardly and rearwardly extending baffle, the material of said front wall between its lower edge and said opening being severed at an intermediate point and the material on each side of the point of severance being bent back upon itself to form tongues spaced inwardly from the front wall of the box, portions of the front edge of said bottom being turned downwardly to form flanges received between said tongues and the front wall of the 10 container, said bottom being provided with a notch extending rearwardly from said flanges and the opening left in the front wall of the box by the folding of said tongues co-operating with 15 said notch to provide access from below to articles supported on the bottom and extending 20 across the notch.

2. The invention set forth in claim 1 with the addition of a base for said container and means 25 for securing the container bottom to said base, said bottom being trough-shaped and having an inwardly extending notch between said flanges, the sides of said notch being formed with inwardly extending triangular portions bent downwardly to close the gap between said bottom and 30 said base.

3. The invention set forth in claim 1 with the addition of a base for said container and means 35 for securing the container bottom to said base.

BERTIS F. HAMILTON.
